UNITED STATES PATENT OFFICE.

CHARLES L. SCHAEFFER, OF CINCINNATI, OHIO.

CONCRETE CONSTRUCTION BLOCK.

Application filed June 12, 1925. Serial No. 36,734.

An object of my invention is to provide a new and novel concrete construction block having a facing of coquina shells.

Another object of my invention is to provide a construction block having a facing so that when a structure using my block, is completed the effect will be very pleasing to the builder and prospective purchaser or owner.

Another object is to provide a process for applying this extraneous facing to a concrete construction block.

Another object of my invention is to provide a simple and economical method for producing the above block.

These and other objects are accomplished by the means described herein and disclosed in the accompanying drawings, in which:

Fig. 1 is a perspective view of a construction block constructed in accordance with my invention.

Fig. 2 is a sectional view on line 2—2 of Fig. 1.

Fig. 3 is a side elevation of the block under construction and showing the mold in cross section.

My improved block comprises a concrete block 5 having an extraneous facing of coquina shells 6. The facing 6 is a composition comprising a proportion of approximately one-third white cement and two-thirds coquina shells. A mold 7, such as disclosed in Fig. 3, may be utilized for making my improved block. A dry mix composed of one-third white cement and two-thirds coquina shells and water, is first spread along the bottom 8 of the mold 7. After this facing 6 has been put into the mold, the mold is then filled with ordinary dry mix concrete

and the contents of the mold is tamped. Immediately on removing the block from the mold, the coquina face of the block is sprayed with water to eliminate excessive cement and to retain the block in a green state. These blocks are kept in a green state by spraying them, as often as required, for about two weeks, after which they are ready for use. The finished concrete block has a smooth facing of coquina shells. The coquina shells give a tint of a very pleasing effect to a structure using these blocks. The coquina shells are found in deposits mixed

with a small quantity of sand. These deposits are used, just as they are found, for making the coquina shell facing.

Coquina shells in natural form are thin, sharp and flaky and whose flat surfaces are very smooth and polished. As pressure is applied to the concrete units in the mold the shells tend to flatten out and overlap very many times in a very small area as they become tightly packed. I have found that this overlapping and packing of the coquina shells produces a facing that is weatherproof, an effect not obtainable with the pebble and coarser aggregates the concrete industry has experimented with heretofore. This weather proofing effect is increased because the flat surfaces of the coquina shells give a much greater surface for cement to adhere to than the uneven or curved surfaces of aggregates now generally in use. Also a facing of coquina shells will give when necessary a sharp knife edge corner which is not possible with the aggregates now generally used, such as small pebbles and crushed stones. Further, a facing of coquina shells presents an almost unbroken surface made up of very many small flat highly polished shells set close together which tend to take up a minimum amount of soot, dirt, etc. I have found that the surface of coquina faced units can be easily cleaned by simply allowing water to run over the surface thereof, therefore ordinary rain will thoroughly clean and brighten the surface of a structure constructed of building units made in accordance with this invention. I have also found that the surface of a structure or building composed of coquina faced units is very clean and bright during a rain and does not show the dark wet spots customary with other concrete and cement faced structures. Coquina faced units give to the building industry a new color, i. e., soft buff, which is very desirable. This color is permanent and regular because it is absolutely natural and is superior to the buff shades now obtainable in clay bricks. Also the color of clay bricks now generally employed is not uniform while the color of coquina faced bricks and units is uniform throughout. By sifting and using shells of a uniform size at least six distinct shades of

buff may be obtained. The smaller shells have the deeper color, while the larger particles have the lighter shade. I have also found that any given shade can be duplicated by using the same size of shells that was formerly used.

What I claim is:

1. A concrete construction block having an exterior facing of overlapping particles 10 having a uniform and permanent natural color, and means for bonding the particles to one another for making a permanent facing.

2. An exterior structural facing composed 15 of thin flaky particles having a natural, uniform and permanent color, the particles being so applied as to expose the edges of the particles to the atmosphere.

3. A concrete construction block having an exterior facing of coquina shells, the coquina shells having a uniform and permanent natural color and forming the facing by overlapping one another, and a binding agent for bonding the coquina shells to one another.

4. An exterior structural facing composed of thin flaky coquina shells having a natural, uniform and permanent color, and sufficient cement for bonding the shells to one another, the coquina shells being so bonded as to expose the edges of the shells to the atmosphere.

In testimony whereof, I have hereunto subscribed my name this 11th day of June, 1925.

CHARLES L. SCHAEFFER.
